MAGNETIC TAPE REEL

Frank T. Walsh, Palo Alto, and Glenn A. Smith, Redwood City, Calif., assignors to Ampex Corporation, Redwood City, Calif., a corporation of California

Application January 2, 1958, Serial No. 49,110

Term of patent 14 years

(Cl. D26—14)

FIG. 1

FIG. 3

FIG. 2

Figure 1 is a perspective view of a magnetic tape reel illustrating our new design;

Figure 2 is a top plan view thereof; and
Figure 3 is an edge view thereof.

We claim:

The ornamental design for a magnetic tape reel, substantially as shown.
